UNITED STATES PATENT OFFICE.

THOMAS E. MURRAY, OF BROOKLYN, NEW YORK.

METHOD OF MAKING REINFORCED MOLDED CONDUITS.

1,387,065.

Specification of Letters Patent.

Patented Aug. 9, 1921.

Application filed January 6, 1921. Serial No. 435,406.

To all whom it may concern:

Be it known that I, THOMAS E. MURRAY, a citizen of the United States, residing at Brooklyn, in the county of Kings and State of New York, have invented a certain new and useful Improvement in Methods of Making Reinforced Molded Conduits, of which the following is a specification.

Conduits of cement or like plastic material have been molded upon a spiral core of wire or the like provided with a cover or wrapping of paper or similar flexible material. My present invention is a method of making a reinforced conduit of this type.

15 In the accompanying drawing—

Figure 1 represents in longitudinal section a portion of the conduit and core therein. Fig. 2 is a transverse section on the line 2, 2 of Fig. 1. Fig. 3 is a similar transverse section, with the spiral core removed.

Similar numbers of reference indicate like parts.

In performing my method, I first make a spiral core 1 of wire or strip metal. Upon said core I apply preferably by wrapping, a cover 2 of paper or similar flexible sheet material. To this cover I next apply a coating 3 of pitch or other viscid adhesive material which will harden. While the pitch coating is still viscid, I wind thereon a spiral wire or metal strip 4, and upon the said coated and wound core I apply plastic cement or concrete 5 to form the conduit body, which I allow to become hard. Finally, I withdraw 35 the core 1.

The spiral wire 4 becomes embedded in the wall of the conduit, and so reinforces the same. The cover 2 remains firmly attached to the spiral 4 and cement 5 by the pitch 3, and so forms a smooth inner surface for the 40 conduit bore.

I claim:

1. The method of making a reinforced molded conduit, which consists in, first, applying to a tubular lining constructed to fit 45 within said conduit, a coating of adhesive material; second, inclosing said coated lining in a spiral strip of metal; third, coating said lining with plastic material to form the conduit body.

2. The method of making a reinforced molded conduit, which consists in, first, producing a spiral metal core; second, covering said core with flexible material; third, applying to said cover a coating of adhesive 55 material; fourth, inclosing said coated core in a spiral strip of metal; fifth, forming upon said coated and covered core a conduit body of plastic material and allowing same to harden, and sixth, withdrawing said spiral 60 core.

In testimony whereof I have affixed my signature in presence of two witnesses.

THOMAS E. MURRAY.

Witnesses:

GERTRUDE T. PORTER,
MAY T. McGARRY.
